By Watson E. Coleman
Attorney

UNITED STATES PATENT OFFICE.

HENRY C. ESTEP, OF INDIANA, PENNSYLVANIA.

GATHERING APPARATUS.

Application filed June 13, 1925. Serial No. 36,921.

To all whom it may concern:

Be it known that I, HENRY C. ESTEP, a citizen of the United States, residing at Indiana, in the county of Indiana and State of Pennsylvania, have invented certain new and useful Improvements in Gathering Apparatus, of which the following is a specification, reference being had to the accompanying drawings.

10 This invention relates to gathering apparatus and has relation more particularly to an apparatus of this kind especially designed and adapted for use in coal mines and more especially in connection with low veins.

15 It is an object of the invention to provide an apparatus of this character which is caused to enter the recess in the face or breast after the shot and to travel along said recess whereby the loosened material within 20 the recess is gathered with a minimum of labor and cost.

It is also an object of the invention to provide a novel and improved apparatus of this general character wherein the gathering medium 25 comprises an endless member provided at points therealong with outstanding fingers, said endless member traversing a fixed path of travel.

Another object of the invention is to provide 30 a device of this kind which is of relatively low height, approximately fifteen inches, and which is constructed in a manner whereby the movable parts comprised therein are driven by a power unit carried 35 by the apparatus.

The invention consists in the details of construction and in the combination and arrangement of the several parts of my improved gathering apparatus whereby certain 40 important advantages are attained and the device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:—

Figure 1 is a view in top plan illustrating an apparatus constructed in accordance with an embodiment of my invention;

50 Figure 2 is an enlarged fragmentary sectional view taken substantially on the line

2—2 of Figure 1, with certain of the parts in elevation;

Figure 3 is a view in side elevation of the structure as illustrated in Figure 1, a side board being removed;

Figure 4 is a fragmentary view partly in plan and partly in horizontal section of the rear portion of the structure as herein set forth;

Figure 5 is a detailed sectional view taken 65 substantially on the line 5—5 of Figure 1;

Figure 6 is a view partly in section and partly in plan and of a somewhat diagrammatic character illustrating the assembly whereby the apparatus is initially entered 70 within a recess;

Figure 7 is a view similar to Figure 6 illustrating the arrangement whereby the apparatus is caused to traverse the recess.

As disclosed in the accompanying drawings, P denotes a base plate of requisite dimensions and configuration, the forward portion of said plate preferably having its side or longitudinal margins in convergence. This plate has direct contact with the 80 room floor or other surface upon which the apparatus rested.

Resting upon the plate P and extending substantially lengthwise thereof is a U-beam B, said beam being arranged at the transverse center of the plate P and provides means whereby strength and rigidity is imparted to the plate P and in practice the side flanges 1 of the beam are approximately 90 four inches high. This beam B is bolted or otherwise suitably fixed to the plate P.

The rear portion of the plate P has secured thereto the transversely disposed parallel I beams A bolted or otherwise secured in applied position with the central 95 portion of each of said beams A cut away at their lower part to bridge the beam B. Each of these I beams A are substantially twelve inches or more in height.

Resting upon and suitably secured to the beams A is a supplemental plate S having its forward end portion 2 disposed downwardly on a predetermined incline and riveted, as at 3, or otherwise secured to the forward portion of the plate P. The plate S extends a desired distance beyond the rear of the beams A and the horizontal portion of the plate S has its side margins defined by the upstanding side boards 4.

55 Rotatably supported by the rear portion 110

of the plate S is a vertically disposed shaft 5, the same being also operatively engaged with the bearing bracket 6 secured to the plate S. Fixed to the upper portion of the shaft 5 is a sprocket 7 around which passes the chain 8. This chain 8 is forwardly disposed and is operatively engaged with a sprocket 9 carried by the upper portion of the vertically disposed shaft 10. This shaft 10 is rotatably supported by the plate S and the beam B, the same being provided with suitable bearings 11 for the shaft. The shaft 10 below the plate S has fixed thereto the worm wheel 12 meshing with a worm 14 carried by the drive shaft 15 driven by the motor M herein disclosed as of an electrical type, said motor M and shaft 15 being supported by the rear portion of the plate P to one side of the beam B.

The lower portion of the shaft 5 has fixed thereto a relatively large sprocket 16 around which passes an endless chain 17 comprised in the gathering medium proper. This endless chain extends forwardly of the plate S along the inclined portion 2 and forwardly of the plate P and around the sprocket 18 rotatably supported by the forward end portion of the plate P. This endless member 17 travels within the guide track 19 the forward portion of which being secured to the side flanges 1 of the beam B and the rear portion of said guide track being suitably secured to the plate S and the inclined portion 2 thereof. Extending outwardly from the chain 17 at predetermined points spaced therealong are the elongated gathering members or fingers 20. Supported by the side portions of the guide track 19 in advance of the shaft 10 are the upwardly and inclined plates 21 having their inner portions continued by the upstanding flanges 22 riveted or otherwise secured one to the other, as at 23. These plates 21 provide means to prevent coal or kindred material being gathered passing from one side of the apparatus to the other.

Rotatably supported by the rear beam A and extending transversely of the apparatus is a shaft 24 having fixed thereto the worm wheel 25 engaging the worm 26 also fixed to the shaft 15. On each end portion of the shaft 24 is loosely mounted a drum 27 adapted to be locked to said shaft for rotation therewith through the medium of a conventional clutch mechanism 28 or to have its rotation retarded or controlled by a conventional brake mechanism 29.

Coacting with each of the drums 27 and adapted to be wound thereupon is a cable or kindred flexible member 30. Suitably positioned below and in advance of each of the drums 27 are the pulleys or blocks 31. After a shot has been made, suitable jacks 32 are arranged within the room adjacent an end of the pocket or recess and at oppo-

site sides of the apparatus with the forward end portion of the apparatus adjacent the face or breast as indicated by broken lines in Figure 6. Both of the drums 27 are then clutched to the shaft 24 causing the cables to wind therearound, said cables being disposed around the forward pulleys 31 and anchored to the jacks 32. This will result in the apparatus being caused to move within the recess or pocket. After this adjustment of the apparatus, one of the jacks 32 is moved to a position as adjacent the opposite or remote end of the recess or pocket as is possible and secured there at a point in alignment with the adjacent forward pulley 31. The second jack 32 is placed at the opposite side of the machine relatively close to the machine and in alignment with the rear pulleys 31. The drum 27 adjacent the first named jack is then clutched to the shaft 15 and the drum 27 at the opposite side of the apparatus unclutched but braked so as to insure the apparatus moving transversely of itself in a direction along the recess or pocket. If the rear end of the apparatus was inclined toward the first named jack at any time, this inclination may be overcome by bringing the drum 27 adjacent the second jack to a standstill so that the operation of the first drum will tend to swing the apparatus bodily about the pivot represented by the rear pulley over which the cable passing to the second jack is passed. During this period the gathering medium is in operation resulting in the loosened coal being carried out of the vein and discharged upon a well-known type of room conveyor. When it is desired to withdraw the apparatus from the recess or pocket, both cables are disposed around the rear pulleys 31 with both of the drums 27 clutched to the shaft 24. This will result in an outward travel of the apparatus.

I also find it of advantage to confine the motor M, shaft 15, and the gears 12, 14, 15 and 16, within a housing 33 which is adapted to be filled with oil and thereby assuring effective operation of these parts.

It will, of course, be understood that this apparatus will operate to the right or to the left without the necessity of making any change whatsoever in the mechanism, it being only necessary to change the cables and reverse the motor.

From the foregoing description it is thought to be obvious that a gathering apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement

and formation of the several parts herein shown in carrying out my invention in practice except as hereinafter claimed.

I claim:—

- 5 1. A gathering apparatus of the class described comprising, in combination, a base plate, transversely disposed beams mounted upon the rear portion of said base plate, a supplemental plate mounted upon the beams, the forward portion of said supplemental plate being downwardly disposed and substantially merging with the forward portion of the first named plate, an endless gathering medium traversing the forward portion 15 of the first named plate and the supplemental plate, and means for operating said gathering medium.
2. A gathering apparatus of the class described comprising, in combination, a base plate, transversely disposed beams mounted upon the rear portion of said base plate, a supplemental plate mounted upon the beams, the forward portion of said supplemental plate being downwardly disposed and substantially merging with the forward portion 25 of the first named plate, a sprocket wheel supported above the supplemental plate, a second sprocket wheel supported above the forward portion of the first named plate, an endless gathering medium operatively engaged with both of the sprockets, and a driving means mounted upon the first named plate below the supplemental plate and in operative connection with the first named sprocket.
3. A gathering apparatus of the class described comprising, in combination, a base plate, transversely disposed beams mounted upon the rear portion of said base plate, a supplemental plate mounted upon the beams, the forward portion of said supplemental plate being downwardly disposed and substantially merging with the forward portion 35 of the first named plate, a sprocket wheel supported above the supplemental plate, a second sprocket wheel supported above the forward portion of the first named plate, an endless gathering medium operatively engaged with both of the sprockets, and a driving means operatively connected with one of said sprockets.
4. A gathering apparatus of the class described comprising, in combination, a base plate, transversely disposed beams mounted upon the rear portion of said base plate, a supplemental plate mounted upon the beams, the forward portion of said supplemental plate being downwardly disposed and substantially merging with the forward portion 45 of the first named plate, a sprocket wheel supported above the supplemental plate, a second sprocket wheel supported above the forward portion of the first named plate, an endless gathering medium operatively engaged with both of the sprockets, and a driving means operatively connected with the first named sprocket.
5. A gathering apparatus of the class described comprising, in combination, a base plate, transversely disposed beams mounted upon the rear portion of said base plate, a supplemental plate mounted upon the beams, the forward portion of said supplemental plate being downwardly disposed and substantially merging with the forward portion 55 of the first named plate, a sprocket wheel supported above the supplemental plate, a second sprocket wheel supported above the forward portion of the first named plate, an endless gathering medium operatively engaged with both of the sprockets, and a driving means carried by the first named plate and operatively engaged with one of said sprockets.
6. A gathering apparatus of the class described comprising, in combination, a base plate, transversely disposed beams mounted upon the rear portion of said base plate, a supplemental plate mounted upon the beams, the forward portion of said supplemental plate being downwardly disposed and substantially merging with the forward portion 65 of the first named plate, a sprocket wheel supported above the supplemental plate, a second sprocket wheel supported above the forward portion of the first named plate, an endless gathering medium operatively engaged with both of the sprockets, and a driving means carried by the first named plate and operatively engaged with one of said sprockets.
7. A gathering apparatus of the class described comprising a base plate, a beam secured thereto at substantially its transverse center and extending lengthwise thereof, an endless gathering member moving over the base plate at opposite sides of the beam, means for moving said endless gathering member laterally in either direction, and upstanding plates operatively supported by the side portions of the beam and inwardly inclined, the inner portions of said plates being connected.

In testimony whereof I hereunto affix my signature.

HENRY C. ESTEP.
